(57) **CLAIM**

The ornamental design for a Bluetooth headset case, as shown and described.

DESCRIPTION

FIG. 1 is a front, right, and top perspective view of a Bluetooth headset case, showing my design.

FIG. 2 is a rear, left, and bottom perspective view of the Bluetooth headset case in FIG. 1.

FIG. 3 is a front view of the Bluetooth headset case in FIG. 1.

FIG. 4 is a rear view of the Bluetooth headset case in FIG. 1.

FIG. 5 is a left side view of the Bluetooth headset case in FIG. 1.

FIG. 6 is a right side view of the Bluetooth headset case in FIG. 1.

FIG. 7 is a top view of the Bluetooth headset case in FIG. 1.

FIG. 8 is a bottom view of the Bluetooth headset case in FIG. 1; and,

FIG. 9 is another front, right, and top perspective view of the Bluetooth headset case in FIG. 1 in an open state.

The broken lines shown in the drawings are included for the purpose of illustrating portions of the Bluetooth headset case that form no part of the claimed design.
